United States Patent

Des. 242,215
Patented Nov. 9, 1976

242,215

FILE GRIP

Elof Granberg, 531 Canal St., San Rafael, Calif. 94901

Filed July 25, 1975, Ser. No. 599,048

Term of patent 14 years

Int. Cl. D8—05

U.S. Cl. D8—94

FIG. 1 is a top elevation showing my design of a file grip;

FIG. 2 is a side elevation thereof;

FIG. 3 is a bottom plan view thereof;

FIG. 4 is a first end view thereof from the left of FIG. 2; and

FIG. 5 is the opposite end view thereof from the right of FIG. 2.

The broken line disclosure of a file in FIG. 2 is for illustrative purposes only.

I claim:

The ornamental design for a file grip, as shown and described.
